APPARATUS FOR OBTAINING FLUID
SAMPLES AND QUENCHING SAME

Benjamin T. Marshall and Mason L. Downing,
Westfield, and Paul J. Harrington, Mountain-
side, N. J., assignors to Standard Oil Develop-
ment Company, a corporation of Delaware

Application April 28, 1949, Serial No. 90,154

4 Claims. (Cl. 137—334)

1

The present invention relates to an apparatus for withdrawing fluid samples from a process vessel. More particularly, the invention relates to a means for withdrawing samples of vaporous materials from a reaction vessel, at elevated temperatures and pressures, by which the reaction process of such materials is substantially quenched at the point of removal of the sample from a reaction vessel. The invention is also concerned with preventing the deposition of reaction or decomposition products in the sampling system. More particularly, the invention relates to an apparatus for sampling hydrocarbon vapors drawn from a cracking furnace where they may be held at temperatures in the vicinity of 900° to 1100° F. or even higher, and under pressures substantially in excess of atmospheric pressure.

It is an object of the invention to provide a sampling valve structure in which flow of the sample withdrawn from a reaction zone may be positively controlled at the source. It is also an object of the invention to provide the means whereby a sample may be quenched as withdrawn so as to reduce its temperature, substantially at the source of the sample, to a degree below that at which reaction of the material may continue, and to thereby prevent the formation of reaction and decomposition products during passage through the sampling system.

In processes involving the high temperature treatment of fluid materials, such as the cracking of hydrocarbons by passing hydrocarbon materials through a cracking coil furnace, it is frequently desirable to ascertain at various points during its passage through the reaction system, the progress of the reaction taking place in the material. The information thus obtained may be utilized for the purpose of adjusting the flow rate of the materials through the heated zone in which the reaction takes place, or for the purpose of regulating and controlling heat input to such zone. Conventional apparatus for this purpose has been found to be generally unsatisfactory for the reason that the samples withdrawn do not truly represent the condition of the material being treated, at the point of withdrawal. The difference in the characteristics of the sample, and the material from which separated, appears primarily to be due to continued reaction in the sample after withdrawal. The material of the sample, retaining a substantial portion of the reaction temperature, continues to react at such temperature during passage through the sampling apparatus, thus produc-

2

ing a change in its characteristics as compared with that of the material at the point of withdrawal. In the apparatus, according to the present invention, this deficiency of the conventional sampling apparatus is substantially overcome.

The invention and its objects may be more fully understood from the following specification when read in conjunction with the accompanying drawings, in which

10. Figure 1 is a vertical section through a sampling device for connection in or to a reaction vessel;
15. Figure 2 is a similar view through a modified form of such sampling device; and
20. Figure 3 is an enlarged vertical section through the valve and seat portion of a modified form of the device as shown in Figure 2.

A sampling valve, according to the present invention, is particularly illustrated by Figure 1. 20 In this figure, the numeral 31 designates a nipple provided for threaded connection in a passageway 5b through a boss 5a on a tube return bend member 5 of a cracking coil. The passage 5b has a slight inward taper from the interior 25 of the return bend 5 toward the threaded portion of the passage, and the threaded portion of the passage is provided with a slight outward taper. The nipple 31 is provided with a flanged portion 31a adapted for engagement by a wrench in order to seat the nipple firmly and in fluid-tight connection in the passageway 5b. The outer end of the nipple 31 at the flange portion 31a is joined as by welding to a valve casing member 32 which extends outwardly from the nipple 35 through the header box 2 and a suitable closure 2a therefor. The outer end of casing 32 is joined, as by welding, to a bonnet assembly including stuffing box member 33 having a central passageway 33a provided with an enlarged shouldered portion 33b at one end to receive the outer end of the casing member 32, and enlarged shouldered portion 33c at the other end to receive a packing material 33d. That portion of the passageway 33a intermediate the enlarged shouldered portions is threaded to engage a similarly threaded portion 34a on a hollow valve stem 34 extended through the stuffing box and the hollow casing 32. The valve stem 34 is extended outwardly beyond the stuffing box member 33 40 and is provided with a valve wheel 34b at its outer end. The hollow valve stem 34 is provided at its inner end with a plug valve member 35 for disposition beyond the inner end of the nipple 31, and adapted to engage a seat 31b provided therefor at the inner end of the nipple.

Ports 36 are provided in the wall of the hollow valve stem opening therethrough into the annular space between the valve stem and the casing 32. Preferably, these ports are disposed substantially at a 45° angle, with reference to the center line of the valve stem and open rearwardly into the annular space around the stem. At the other end of the valve stem intermediate the valve wheel 34b and the stuffing box member 33, ports 37 open outwardly from the interior of the valve stem, through the wall thereof, into the hollow interior of a header member 38.

The header member 38, as shown, is formed by means of annular, disc-shaped top and bottom elements 39 and 40 respectively, separated and joined by means of a cylindrical wall element 41, the valve stem 34 extending through the central opening in each of the top and bottom elements 39 and 40. The center opening in the top element 39 is provided with an enlarged portion, lying substantially within an exterior boss 39a, in which is disposed a packing material 39b, compressed and held in fluid-tight engagement with the valve stem by means of a flanged gland member 39c. The gland member 39c is made to compress the packing material 39b by means of nuts 39d acting on the threaded outer ends of stud bolts 39e. The bottom element 40 is provided with an annular boss 40a concentric with the central opening through such element, which boss serves as a gland member to compress and hold the packing material 33d in fluid-tight relation to the valve stem, pressure being applied for this purpose by means of stud bolts 40b threaded into the bottom element 40 and extending outwardly through bolt holes in a flanged portion on the element 33 for engagement by nuts 40c.

Provision is made for the supply of a quenching fluid to be introduced into the hollow header member 38 by means such as the coupling element 41a secured as by welding in a suitable passageway through the wall of the element 41, the coupling 41a being interiorly threaded to receive a supply conduit such as conduit 7. An alternate location for the conduit 7 may be provided as by means of coupling element 41b, and a plug member 41c provided to close either one of the coupling elements 41a or 41b, whichever is not connected in the supply system. Means for a supplementary supply of quenching fluid is provided by coupling elements 42 and 43 joined to the casing 32 in fluid-tight relation as by welding. Ports 32c and 32b in the wall of the casing 32 providing an inlet and an outlet, interchangeably, from the interior of the casing through the coupling elements and lines 9 and 10 respectively. Quenching liquid from the interior of the casing, and the sample material introduced through the nipple 31 may be discharged, with quenching liquid introduced through line 9, by way of line 10.

In the operation of the valve as shown, a quenching fluid is introduced normally through a line 7 into the header 38 and thence through the ports 37 into the interior of the valve stem. Simultaneously, a supplementary supply of quenching fluid may be introduced through the line 9, if desired. The valve is then opened by threading the valve stem into the casing and passageway 33a by means of the handle 34b, the plug 35 thus being moved inwardly away from the seat 31b admitting a stream of material from the return bend 5 through the passage 5b in boss 5a, and the nipple 31. The sample thus admitted passes through the annular passage

in the casing 32 surrounding the valve stem 34 and is quenched by means of quenching fluid issuing from the ports 36 at the inner end of the stem adjacent the plug 35. The sampled material along with the quenching fluid flows through the annular passageway in the casing 32 and is discharged through the port 32b and the conduit 10. As indicated, if desired, additional quenching fluid may be passed through the casing at this point by means of the conduit 9, or, if desired, the coupling 42 may be provided with a suitable closure plug. It is also contemplated that, if found necessary, the connection of the line 9 and line 10 to the casing 32 may be made through an eductor mechanism for the purpose of producing a slightly negative pressure in the annular passage through the casing 32, thereby tending to accelerate removal of the quenching fluid and the sample passed therethrough. When it is desired, the valve may be flushed with a cleaning liquid, or a fluid such as steam, by introducing such fluid through lines 7 and 9. If sufficient pressure is applied to the cleaning fluid, it may be discharged into the return bend 5, otherwise it may be exhausted through line 10.

In the apparatus, as illustrated by Figure 2, the numeral 51 designates a nipple provided to be threaded into a passageway 5b through the boss 5a and having an end portion 51a provided with an annular valve seat member 51b and an inwardly faced valve seat 51c. In this modification, a two part casing element 52 is provided, the parts 52a and 52b being joined by a 4-way coupling member 53. The inner portion 52a of the casing element is joined at its inner end, as by welding, to the nipple member 51 and at the outer end is provided for threaded engagement with the coupling 53. The outer portion 52b of the casing 52 is provided for threaded engagement at its inner end with the coupling 53 in opposed relation to the outer end of the portion 52a. The outer end of the portion 52b is provided to serve as a stuffing box, and is adapted to receive a packing gland member 54, packing 55, and a stop member 56, which may be an annular shoulder portion in the casing or a separate member rigidly secured therein. This member 56 and a comparable member 57 at the inner end of the casing also serve as bearings for a valve stem 58 extending concentrically through the casing 52. The packing 55 may be compressed between the element 56 and the gland 54 to bear against the valve stem 58 and provide a fluid-tight seal therewith, by means of bolt and nut members 59 passed through co-incident bolt holes in opposed flange portions on casing portion 52b and gland 54.

In place of a bonnet for the valve, a yoke member 60 is provided which is secured to the valve casing as at 60a and extends outwardly beyond the end of the gland 54. The outer end of the yoke 60 is provided with threaded passageway 60b to receive the end of the valve stem, also threaded. By this means, the valve stem is engaged in the passageway for reciprocal movement of the stem when rotated by means of the valve wheel 61. The inner end of the stem is provided with a conical valve portion 62 adapted to be seated against the inwardly faced seat 51a in the annular member 51b. In the form of the valve, as illustrated, quenching liquid is supplied through the coupling 53 by way of the line 9 and is discharged therefrom by way of the line 10. Preferably, this connection is made through a conventional form of eductor mechanism for the

purpose of creating a negative pressure in the casing portion 52a and the nipple 51, whereby the material entering the nipple through the member 51b is quickly withdrawn and quenched. Operation of the valve described, and illustrated by Figure 2, is otherwise comparable to that set forth with reference to Figure 1. The line 9 is connected to a source of quenching fluid, while the line 10 is connected to suitable means for recovering the sample.

In the modification illustrated by Figure 3, the hollow valve stem 34 is provided at its inner end with a plug valve member 61, comparable to the member 35 of Figure 1, but hollow, and opening into communication with the hollow valve stem. The stem 34 in this form opens into the valve 61, ports 62 in the valve member 61 being substituted for the stem ports 36 shown in Figure 1. The ports 62 are disposed so as to remain open at all times, being located beyond the seating face 61a of the valve member, and the valve seat 31b. By this means a continuous stream of quenching fluid may be discharged through the passageway 5b when the valve is closed tending to prevent deposition of reaction products between the valve member and the walls thereof, and preventing seizure of the valve member in the passage.

When the valve is opened, the ports 61a tend to direct the flow of quenching fluid toward the entrance to the nipple 31 and the fluid and sample may be discharged into the casing under pressure from the coil. Also by introducing the quenching fluid beyond the valve seat 31b, small particles of foreign matter may be more readily prevented from depositing on the seat.

What is claimed is:

1. A valve structure, comprising a hollow casing, having an inner end and an outer end, a valve inlet port in the inner end of said casing, a valve seat in said port facing outwardly therefrom, a hollow header member carried on the outer end of said casing in fixed relation thereto, a hollow valve stem longitudinally of said casing extending outwardly therefrom through said header member and disposed in annularly spaced relation to said casing, a valve member on said stem disposed exteriorly of the casing and engageable with said valve seat by reciprocal movement of the stem, a fluid-tight seal for said stem at the outer end of said casing, said seal also separating the interior of said casing from that of said header, inlet ports in said stem communicating between the interior of said header member and the interior of said stem, discharge ports in said stem adjacent said valve inlet port communicat-

ing with the interior of said stem and opening angularly outward therefrom substantially in the direction of flow through said port into the casing, an outlet from said casing intermediate the ends thereof, and means for reciprocally moving said stem longitudinally of said casing.

5 2. A valve structure according to claim 1, in which the discharge ports communicating with the interior of said stem open therefrom into the 10 interior of the casing inwardly of the valve port.

3. A valve structure according to claim 1, in which the discharge ports communicating with the interior of said stem open therefrom through said valve member beyond the surface of said 15 valve seat when the valve member is in engagement therewith.

4. A valve structure, comprising a hollow casing element, having an inner inlet end and an outer end, a valve inlet port at the inner end of said casing and a valve seat in said port facing outwardly therefrom, a combination header and packing gland member in rigid, fluid-tight engagement with the other end of said casing, a hollow valve stem extended through said header-gland member and casing, in threaded, fluid-tight relation to said header-gland member and reciprocally moveable therethrough, a valve member on said stem disposed exteriorly of the casing for engagement with said seat by reciprocal movement of the stem, inlet ports in said stem communicating between the header and interior of the stem at one end and discharge ports communicating with the interior of the stem at the other end to open angularly outward therefrom substantially in the direction of flow through said inlet port into the casing, conduit means for supplying a fluid material through the header and stem, conduit means, intermediate the ends of said casing, opening from the casing to discharge fluids therefrom, an operating element for said valve stem, and supplementary conduit means, intermediate the ends of said casing, for introducing a fluid material into said casing exteriorly of said hollow valve stem and intermediate the 40 inlet and discharge ports therein.
